UNITED STATES PATENT OFFICE.

BENJAMIN F. NEELY, OF COLTON, CALIFORNIA.

BOTTOM FOR COTS, HAMMOCKS, &c.

SPECIFICATION forming part of Letters Patent No. 541,872, dated July 2, 1895.

Application filed April 10, 1895. Serial No. 545,231. (No model.)

To all whom it may concern:

Be it known that I, BENJAMIN F. NEELY, a citizen of the United States, residing at Colton, in the county of San Bernardino and State of California, have invented certain new and useful Improvements in Bottoms for Cots, Hammocks, and the Like; and I do hereby declare the following to be a full, clear, and exact description of the invention, such as will enable others skilled in the art to which it appertains to make and use the same.

My invention relates to improvements in bottoms for cots, hammocks and the like, and its object is to provide as an article of manufacture a bottom piece which may be attached to any suitable frame work for the purpose of producing a springy cot, hammock or bed bottom.

The invention consists of a sheet of canvas cut to the proper shape and dimensions, having sewed along its outer edges a cord to which is attached at the end and side by means of loops or rings, springs and hooks formed with attaching devices at their outer ends, by means of which the bottom may be secured to any frame-work for the purpose for which it was designed.

The invention also consists in other details which will be clearly brought out hereinafter.

In the drawings forming a part of this specification, Figure 1 represents a top plan view of my bottom detached. Fig. 2 is a section along one edge thereof, showing the cord secured therein.

Like reference numerals indicate like parts in the two views.

1 represents a sheet of canvas or other fabric, of which the bottom proper is to be made up, having sewed in its outer edges a cord 2 to which is attached along the ends and sides a series of loops or rings 3 having connected to them coiled springs 4 and hooks 5. The coiled springs 4 are formed at their outer ends with a loop or hook 6 by means of which the

same may be attached to any frame work for 45 the purpose of producing a cot or hammock.

In using my device as a cot the springs 4 at the ends and sides of the bottom 1 will be attached to suitable parts of the frame work of the cot and a resilient bottom will be provided therefor. If it is not desired to have so much spring the hooks 5 may be attached in place of the springs 4, or both may be secured to the frame work for the purpose of producing a springy bottom and at the same 55 time preventing undue sagging thereof. I may, if I desire, connect the outer ends of the springs 4 or the hooks 5, or both, by a suitable cord 7, which may itself be attached to hooks upon any frame work.

Of course, if the device is to be used as a hammock the end pieces alone will be attached to a supporting cord or rope.

The invention is very simple in construction, but by it a useful and convenient bottom 65 is produced at a small cost.

Having now described my invention, what I claim as new, and desire to secure by Letters Patent, is—

As an article of manufacture, the herein described bottom for cots, hammocks and the like, consisting of a sheet of canvas or other suitable fabric cut to the proper shape and dimensions, binding cords secured to the outer edges of said canvas, and extending entirely 75 around the outside thereof metallic loops fastened to said cords at intervals, springs and hooks secured to said loops, and a cord passing through the outer ends of said springs and hooks, substantially as and for the purpose 80 described.

In testimony whereof I have signed this specification in the presence of two subscribing witnesses.

BENJAMIN F. NEELY.
